[57] CLAIM

The ornamental design for a case for data/voice/fax concentrator, as shown and described.

DESCRIPTION

FIG. 1 is a perspective view of a case for data/voice/fax concentrator showing my new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view thereof; and,
 FIG. 7 is a left side elevational view thereof.
